UNITED STATES PATENT OFFICE.

JOSEPH M. SCHUTZ, OF CHICAGO, ILLINOIS, ASSIGNOR TO JOSEPH M. SCHUTZ, INC., OF CHICAGO, ILLINOIS, A CORPORATION OF ILLINOIS.

AUTOMOBILE HOOD CLAMP.

Application filed May 29, 1920. Serial No. 385,111.

To all whom it may concern:

Be it known that I, JOSEPH M. SCHUTZ, a citizen of the United States, and a resident of Chicago, in the county of Cook and State of Illinois, have invented certain new and useful Improvements in an Automobile Hood Clamp, of which the following is a specification.

My invention relates to an improved clamp particularly adapted for clamping or holding down an automobile hood, though it will be obvious that my improved clamp can be advantageously employed in other situations.

The object of my invention is to provide an automobile hood clamp which shall be capable of being operated easily; which shall hold the hood clamped down with a strong spring pressure; which shall be slightly in appearance, and which will drop down or swing freely to a position where it will not interfere with free access to the space beneath the hood when it is disconnected from the hood.

A particular feature of my invention resides in the provision of a clamping lever so arranged that its fulcrum can be brought into close relation to the projection on the hood to be engaged and whereby, though the lever is not long, the clamping force which can be applied is very great. Another feature of particular importance relates to the mechanical construction of the clamps by which I am enabled to rapidly and cheaply manufacture these clamps by means of the usual punch press method, the main parts being readily produced out of flat stock. A further feature relates to the means which I employ for holding the clamp so that it cannot rattle and incidentally holding the lower edge of the hood inwardly and preventing rattling of same.

My invention will be more readily understood by reference to the accompanying drawings forming part of this specification and in which:

Figure 1 is a fragmentary side elevation of the front end of an automobile provided with hood clamps made in accordance with my invention;

Figure 2 is a fragmentary sectional view taken on the line 2—2 of Figure 1;

Figure 3 is a side elevation of one of the clamps and is a sectional view taken on the line 3—3 of Figure 2 showing the clamp in holding position; and

Figure 4 is a view similar to Figure 3 showing the clamping levers as they appear when brought into contact with the knob on the hood in the operation of clamp- 60 ing the hood down.

One fundamental idea underlying my invention relates to the peculiar arrangement of levers and fulcrums by which I am enabled to clamp the hood down with a very 65 great pressure and to accomplish the opening and the closing of the clamp with very little effort.

In said drawings, 1 represents the hood of an automobile, the lower edges of the 70 sides of which are arranged above and usually out of contact with the side members 3 of the chassis of the automobile. Above the lower edge of the side of the hood at a suitable height I provide projections 4 which 75 are adapted to be engaged by the clamping devices 5 to hold the hood down.

The clamping devices comprise two main members or levers 6 and 7. The member 7 constitutes the operating lever and is 80 pivotally connected at 8 between its ends to the free end 9 of the member 6. The member 6 constitutes a holding member and is connected at its lower end 10 to the frame 3 at a point vertically beneath the 85 projection or knob 4. The member 6 is connected to the chassis by means of a staple-like member 11 which has its ends securely riveted or otherwise fastened in the horizontal plate of the frame member 90 3 and stands up from said plate. The member 6 comprises an open sided box-like lower end 13 within which is housed a compression spring 14. The part 13 is formed out of a single strip of metal bent between its 95 ends to form a bottom wall 15 and side walls 16. Adjacent to the upper end 17 these side walls are bent inwardly into close relation to each other and are permanently or rigidly connected together by means of 100

a rivet 18. I space the ends 17 apart sufficiently to admit the connecting end 19 of the member 7 between them by a spacer 20 which is of the same thickness as the member 7 and held in position by the rivet 18. The end 19 of the lever 7 projects beyond the pivot 8 and in clamping position extends between the ends 17 of the side walls of the member 6.

10 The member 6 is connected to the staple 11 by means of a rod 21 which extends longitudinally between the side walls 16 and through a central perforation in the bottom wall 15. The upper end 22 of the rod 21 is threaded and engages a nut member 23 which is guided between the sides 16 and is provided with projecting parts 24 which overlap and engage the edges of the walls 16 for holding the member in place. The 15 spring 14 is mounted within the box surrounding the rod 21 and is confined between the nut member 21 at its top and the bottom wall 15 at its lower end. The free lower end of the rod 21 is formed into an eye 25 around the staple 11 and is thus permanently secured to same. This form of connection permits the clamping device as a whole to drop freely down and away from the hood, as indicated in dotted lines 20 in Figure 2, and it does not interfere with free access to the space beneath the hood. The upper end 17 of the side walls of the member 6 are bent or curved edgewise or in their planes and parallel with each other 25 upon a relatively small radius so that these curved ends which form a hook may be centered upon the projection 4. The end 19 of the lever 7 is likewise bent or curved edgewise to lie within the ends 17 when the 30 device is in clamping position as shown in Figure 3.

The projections or knobs 4 each comprise a flat flange-like base 26, a shank 27 and a head 28. In the form shown, these knobs 45 are formed up out of sheet metal, the hollow shank having an out-turned circumferential flange 29 at its outer end around and beneath which the inner edge of the hollow head 28 is formed. The knob is secured to the hood by rivets 30 which secure the base flange 26, and a reinforcing plate 31 may be provided within the hood for strengthening the hood at this point. The shank 27 is preferably tapered from the base to the head, being smaller just beneath the head. This tapered form makes a knob which is strong, rigid and light, and provides a downwardly and outwardly inclined clamp contacting surface on its upper side 50 which tends to cause the clamp to slide towards and into contact with the head in the clamping operation, and as the clamp is held down in clamping position by the spring 14 it is held with considerable pressure 55 against the head and thus held against mov-

ing about or striking the hood and making a rattling noise when the automobile is running.

To assist in the tight clamping of the hood I preferably arrange the staple 11 closer to the side of the hood than the position of the upper end of the clamp on the shank 27 so that the pull of the clamp is slightly inwardly upon the hood as well as downwardly, and consequently the lower 75 edge of the hood is held against sidewise movement as well as being held down and the possibility of any rattling of the hood is eliminated.

The shank 27, as best shown in Figure 4, 80 is of small diameter relatively to the curvature of the ends of the members 7 and 8 and the shank serves as a fulcrum around which to pull the lever in the clamping operation. The pivoted connection of the two 85 members being at the extreme end of the curved part of the member 6, forms a movable fulcrum in connection with the lever 7. It will be understood from Figure 4 that the great compression or locking pressure 90 of the device is attained by the close proximity of the shank 27 to the pivoted connection of the two levers and this makes the operation of prying the hooked end of the member 6 over the projection 4 very easy. 95 Even the initiation of the locking effort is easily accomplished. As the member 7 is swung down from the position shown in Figure 4 to the final position shown in Figure 3 the pivoted connection between the 100 two members is forcibly raised over the shank 27, thus continually shortening the length of the lever between these two points until the pivot 8 is carried over the shank 27, at which time the force of the spring 14 105 is sufficient to draw the hooked end of the member 7 close around the shank 27 and serves as soon as the lever 7 is released to force the operating end of the lever 7 into firm and close contact with the lever end of the member 6. By this means the lever 7 110 is prevented from rattling in use. It will be clear that the clamping device is self-adjusting to engage and hold the projection 4 even though the height of the projection 115 may not be at a definite or predetermined point. The clamp can be properly operated if the shank 27 enters within the curved end of the lever 7, as the clamp is lifted into operating position, as shown in Figure 4, 120 where I have illustrated the shank 27 at several different heights.

In opening the clamp the free end 32 of the lever 7 is swung up and the curved end 125 19 is thus pressed forcibly down against the shank 27 thus forcibly lifting or prying the member 6 upwardly against the force of the spring 14 and as the lever 7 is lifted higher the curved end slides around the shank 27 and forces the pivoted connection 8 over 130

and off of the shank 27 until it is in the position shown in Figure 4, in which position the clamp is free to drop down out of the way.

5 The tension of the spring 14 can readily be adjusted by rotation of the member 6 and the nut 23 upon the upper end of the rod 21 in an obvious manner when the clamp is free of the projection 4, thus screwing or 10 unscrewing the nut 23 on the rod 21.

The large opening 33 which I provide in the outer end 32 of the lever 7 forms a convenient finger hold for operating the device.

15 The device, as seen in elevation from the side of the hood, is quite symmetrical and slightly and is somewhat ornamental.

20 The knobs 4 project far enough from the side surface of the hood to serve as lifting handles and eliminate the necessity of other lifting handles being provided.

In the usual automobile construction there is but a limited space between the front wheel fender and the adjacent side of the hood and the hood clamps are situated 25 in and must be operated in this limited space. For this reason I make my device to swing freely on its staple 11, parallel with the side of the hood in the hood locking and unlocking operations instead of 30 swinging from and toward the hood as in the usual hood clamp. This permits the employment of a relatively long operating lever especially as the lever depends or folds 35 downwardly out of the way in the hood clamping position, and the device as a whole is in a most convenient position to be operated. Furthermore, the curved 40 end of the operating lever, which first engages with the projection 4 in the hooking operation, tends to hold the pivoted connection 8 close to the projection as the lever is 45 swung over to complete the engagement of the clamp with the projection. This feature is of value in that it makes the hooking operation very easy as power applying portion of the lever is always wanted of minimum length.

As may modifications of my invention will readily suggest themselves to one skilled in the art, I do not limit or confine my invention to the specific structures herein shown and described.

I claim:

1. In a clamping device, an extensible 55 member having a hooked end yieldingly held against extension, the opposite end adapted to be loosely connected to a relatively fixed member, a lever having an end curved to substantially conform with the 60 hook and pivotally connected between its end to the free end of the hook, a projection on a relatively movable member adapted to be engaged by said hook, the curved end of the lever adapted to act as a guide in engaging 65 the hook with the projection and to

lift the hook off of the projection in the disengaging action.

2. A device for clamping down an automobile hood comprising an extensible member adapted to be loosely connected at one 70 end to the chassis and having a hook at the opposite end, a spring for yieldingly holding said member against extension, a headed projection on the hood over which said hook engages, a lever pivoted to the free end of 75 the hook adapted to be swung over said projection and brought down substantially parallel with said member for prying the hooked end over the projection, and said lever having an end projecting past the 80 pivotal connection for engagement with the projection for holding the operating end of the lever swung inwardly into contact with such member when in latched position.

3. In a device of the kind described, a 85 yielding member having a curved hook at one end for engagement over a projection on the hood, the opposite end being pivotally connected to the chassis at a point vertically beneath said projection, means for prying 90 said hook over said projection comprising a lever pivotally secured to the depending end of said hook, and having an end curved similarly to said hook with a smooth inner surface and adapted to practically coincide 95 with the hook when the device is in latching position, a lever having a freely extending operating end adapted to be swung from an upright position to a depending position in contact with said projection to pry the hook 100 over the projection, the curved end of the lever operating to pry the hook off of the projection when the lever is lifted.

4. In a device of the kind described, a member formed of strap metal and having 105 a hook at one end, the opposite end formed of two parallel side walls, a compression spring between the side walls, a nut member guided on the edges of the side walls, a rod extending longitudinally between the 110 side walls and having an end in threaded engagement with the nut, the spring compressed between the nut and the bottom of said member, the free end of the rod formed for connection with a staple on a relatively 115 fixed part, a projection on a relatively movable part to be engaged by said hook, a lever pivotally mounted on the free end of said hook and having an end adapted to substantially coincide with the hook when the 120 device is in clamping position, the lever being adapted to pry the hook over the projection as it is swung from a vertical position to a depending position.

5. In a device of the kind described, a 125 projection extending out from the side of the hood substantially at right angles thereto and a yielding member having a hook at its free end, a lever pivoted to the free end of the hook for lifting said hook over said 130

- projection and said lever and member being movable in a plane substantially parallel with the side of the hood for engaging and disengaging said projection, the lever having an end adapted to engage the top of the projection and to hold the handle in anti-rattling engagement with the body of the devices, and in substantial parallel relation thereto.
6. In a device of the kind described, a projection on the hood, an extensible member pivotally mounted on the chassis, a spring yieldingly holding said member against extension, said member having a curved hook of relatively large radius on its free end, a lever having an operating end curved similar to the curve of the hook and pivoted to the free end of the lever at a point within the curved part of the lever whereby in the engaging operation there is provided sufficient latitude of

relative movement to permit the lever to engage the projection at different heights and to cause a forcible extension of the hook member.

7. A device for clamping an automobile hood to a chassis comprising a body adapted to be loosely connected to the chassis at one end, a spring retained extensible member having a curved hook at one end carried by said body, a round bodied projection on the hood for engagement by the hook, a lever rigidly mounted between its ends on the free end of the curved hook and having an end curved similarly to the hook and normally extending substantially coincident therewith when the device is in clamping position as and for the purpose specified.

In witness whereof I have hereunto signed my name this 27th day of May, A. D. 1920. 40

JOSEPH M. SCHUTZ.
